(57) **CLAIM**

The ornamental design for a rowel for bull riding spur, as
shown and described.

DESCRIPTION

FIG. 1 is a top, back, left, perspective view of a rowel for
bull riding spur, showing our new design in a condition for
use;

FIG. 2 is a top, back, right, perspective view thereof;

FIG. 3 is a top, front, right, perspective view thereof;

FIG. 4 is a top, front, left, perspective view thereof;

FIG. 5 is a bottom, left perspective view thereof;

FIG. 6 is a back elevation view thereof;

FIG. 7 is a front elevation view thereof;

FIG. 8 is a left side elevation view thereof;

FIG. 9 is a right side elevation view thereof;

FIG. 10 is a top plan view thereof; and

FIG. 11 is a bottom view thereof.

FIG. 12 is a top, front, left, perspective view of the rowel of
FIG. 1;

FIG. 13 is a back elevation view thereof;

FIG. 14 is a front elevation view thereof;

FIG. 15 is a left side elevation view thereof;

FIG. 16 is a right side elevation view thereof;

FIG. 17 is a top view thereof; and,

FIG. 18 is a bottom view thereof.

In the drawings, the broken lines on the rowel for bull riding
spur depict unclaimed elements on the rowel that form no
part of the claimed design. The broken lines showing a spur
and spur hardware depicts environmental subject matter and
forms no part of the claimed design.

1 Claim, 18 Drawing Sheets
